UNITED STATES PATENT OFFICE.

ERNEST B. JONES, OF WEST CANAAN, NEW HAMPSHIRE.

MORTISING-JIG.

1,210,942.

Specification of Letters Patent.

Patented Jan. 2, 1917.

Application filed March 25, 1916. Serial No. 86,786.

To all whom it may concern:

Be it known that I, ERNEST B. JONES, a citizen of the United States, residing at West Canaan, in the county of Grafton and State of New Hampshire, have invented 5 certain new and useful Improvements in Mortising-Jigs, of which the following is a specification.

This invention comprehends certain new 10 and useful improvements in boring and drilling appliances, and relates particularly to a mortising jig designed for use by carpenters and the like as a guide for any ordinary auger bit, in mortising for locks and 15 doors or in connection with any other work where a number of holes are required in true alinement with each other.

The invention has for its primary object 20 a durable and efficient construction of device of this character which will embody comparatively few parts that may be very easily manufactured and readily assembled and which will not be liable to get out of order and wherein the required adjustments 25 may be very easily made and the parts readily held in their adjusted positions, so that the holes may be bored in true alinement with each other and at the desired distances apart.

30 The invention has for a further object an improved device of this character provided with improved means whereby the guide member for the auger bit may be very easily adjusted both longitudinally and laterally as required, and held at its desired 35 longitudinal and lateral adjustments without any danger of slipping.

A still further object of the invention is 40 a mortising jig in which there are a number of collets of varying internal diameters according to the size of the auger bit used and in which these collets are detachably connected to the collet holder of the apparatus in a manner which will preclude all liability 45 of accidental displacement or detachment, while at the same time the parts are so correlated that one collet may be very easily slipped out and replaced by another with very little work. And the invention also 50 aims to generally improve devices of this class so as to render them more useful and commercially desirable.

With these and other objects in view, as 55 will more fully appear as the description proceeds, the invention consists in certain constructions, arrangements and componen-

tions of the parts that I shall hereinafter fully describe and claim.

For a full understanding of the invention, reference is to be had to the following 60 description and accompanying drawings, wherein,

Figure 1 is a perspective view of a mortising jig embodying the principles and improvements of my invention. Fig. 2 is a 65 plan view of the frame of the device, the cross-head and its concomitant parts being omitted. Fig. 3 is a detail view of the cross-head. Fig. 4 comprises a side and inner or bottom end view of one of the collets 70 used. Fig. 5 is a detail view of a clamping ring employed for securing the collet holder at the desired lateral adjustment on the cross-head of the frame. Fig. 6 is part section and part elevation showing said clamping ring and collet holder detached from the cross-head. Fig. 7 is a sectional side elevation of the collet holder and collet therein. Fig. 8 is a detail sectional view through the cross-head, and Fig. 9 is an inner or bottom plan view of the collet holder hereinafter more specifically referred to.

Corresponding and like parts are referred to in the following description and designated in all of the views of the accompanying drawings by like reference characters.

My improved mortising jig comprises a frame or vise designated "A" as a whole, and including longitudinally spaced cross bars 1 which are preferably in the form of 90 castings with angularly disposed parallel end arms 2 and 3. A preferably wooden clamping member 4 is secured by screws or similar fastening devices to the inner side of one pair of end arms 2 of the bars 1 and 95 the other arms 3 of said bars at corresponding ends are formed with screw-threaded apertures through which the threaded shanks 5 of adjusting screws 6 work, said screws being provided at their outer ends 100 with hand-wheels 7 or the like, by which they may be easily turned. The inner end of each adjusting screw 5 is swiveled in a bearing 8 which is provided with a base plate 9, that is secured by screws or similar 105 fastening devices to a preferably wooden clamping member or board 4' that is complementary to the board 4, these two boards constituting clamping members of the device and, being of wood, serve to hold the 110 frame or vise securely in place without any danger of marring fine woodwork.

The bars 1 are connected together, in spaced relation, by means of longitudinally extending rods 10, the ends of which are received and secured within apertured bosses 11 formed on the cross bars 1 at the ends thereof, as clearly illustrated in Figs. 1 and 2, and these rods 10 not only serve as parts of the frame itself, to hold the bars 1 in fixed relation to each other, whereby a firm framework is produced, but they also serve as guides for a cross-head 12. The cross-head 12 is designed to extend from one rod 10 to the other, and is formed on one face with correspondingly projecting laterally extending flanges 13 that are provided at their ends with apertured ears 14 through which the rods 10 extend, whereby the cross head may slide longitudinally upon the rods and to hold the cross-head in different adjusted positions, I provide one or more set screws 15 extending through the cross-head 12 and designed to impinge against the rods, only one of these sets screws being employed in the present instance, although it is to be understood that the invention is not limited in this regard. The cross-head 12 is also provided with correspondingly projecting flanges 16 that extend laterally as best illustrated in Fig. 1, in a direction opposite to the flanges 13, each of the flanges 16 being formed with an undercut or channel 17, and said channels facing each other, as shown. These channels 17 serve to guide and receive a base plate 18, which forms part of a collet holder 19, said collet holder being of cylindrical formation, as shown, and being exteriorly screw-threaded, as at 20, whereby a clamping nut or ring 21 may be mounted thereon. This clamping nut 21 is designed to bear frictionally against the outer faces of the flanges 16 when screwed thereagainst, so as to fasten the collet holder in the desired laterally adjusted position. The cylindrical body portion of the collet holder 19 is also interiorly screw-threaded, as best indicated at 22 in Fig. 7, to receive an externally screw-threaded collet 23, and it is to be understood that there are a number of these collets provided with each jig, so that the same device may be used to guide auger bits of different sizes or diameters.

From the foregoing description, in connection with the accompanying drawings, the operation of my improved mortising jig 55 will be apparent. In the practical use of the device, the vise is applied, for example, to the edge of the door where the mortise is to be made with the clamping members 4 and 4' embracing the edge of the door between them, the frame of the vise being very easily and quickly secured in position by the manual operation of the adjusting screws 6. Then the cross-head 12 is adjusted, as required, longitudinally on the 60 rods 10 and held in the desired position by

means of the set screw 15, and the collet holder adjusted laterally and held in the desired position by means of the clamping nut 21. Thus it will be seen that the desired adjustments may be very easily effected, first by shifting the collet holder laterally upon the cross-head and then locking it securely in place and subsequently by shifting the cross-head itself longitudinally upon the guide rods 10 to bore one hole after another, the holes being bored in absolutely true alinement with each other and at any desired distances apart, according to the amount of adjustment of the cross-head upon the rods.

The device is composed of comparatively few parts that are not liable to get out of order and that can be very readily assembled and the required adjustments made with considerable facility.

While the accompanying drawings illustrate what I believe to be the preferred embodiment of my invention, it is to be understood that the invention is not limited thereto, but that various changes may be made in the construction, arrangements and proportions of the different parts without departing from the scope of the invention as defined in the appended claims.

What is claimed is:

1. A mortising jig, including a vise, comprising spaced bars formed at their ends with angularly disposed arms, a clamping member secured to the arms at one end of said bars, adjusting screws working through the other arms of said bars, a clamping member connected to the inner ends of said screws, guide rods connecting said bars together in spaced relation to each other, a cross-head slideable longitudinally on said rods, means for holding said cross-head in different positions on said rods, and a collet holder carried by said cross-head, the cross-head being provided with flanges formed with laterally extending channels facing each other, and the collet holder being provided with a base plate slideable in said channels and with a clamping nut adjustable on the holder and designed to bear against said flanges whereby the collet holder may be fastened at different lateral adjustments on the cross-head.

2. A mortising jig including a vise, provided with guide rods, a cross-head formed on one face with laterally extending flanges having apertured ears receiving said guide rods and by which the cross-head is slideable on said rods, means for holding the cross-head at different adjustments on said rods, the cross-head being formed on its opposite face with laterally disposed flanges formed with channels, a collet holder having a base plate received in said channels, whereby it is mounted for sliding movement laterally on the cross-head, the collet holder also em-

bodying a cylindrical body portion having external screw-threads, and a clamping nut working on said screw-threads and adapted to bear against the last named flanges where-
5 by the collet holder may be fastened in dif-
ferent adjusted positions.

3. In a mortising jig, a collet holder pro-
vided with a base plate, in combination with
10 a cross-head having guides in which the
base plate is receivable, said collet holder be-
ing also provided with a cylindrical body
portion having external screw threads, a
clamping nut working on said screw threads,
15 for the purpose specified, said body portion
being also internally screw-threaded, and a
collet receivable in said cylindrical body
portion and externally screw-threaded to en-
gage the internal threads of the holder.

4. A mortising jig of the character de-
scribed, comprising spaced bars having an-
gularly disposed end arms and formed at its
20 end with apertured bosses, guide rods re-
ceived in said bosses and securing the cross-
bars together in spaced relation to each
25 other, a board fastened to the inner face of

the arms at corresponding ends of the cross
bars, adjusting screws working in the other
arms of said bars, another board secured to
the inner ends of said screws, a cross-head
20 formed with apertured ears by which it is
mounted for sliding movement on said rods,
a set screw working through said cross-head
and adapted to impinge upon one of said
rods to hold the cross-head in different ad-
25 justed positions, the cross-head being formed
on one face with laterally extending flanges
provided with channels, and a collet holder
having a base plate movable in said chan-
nels and a cylindrical body portion formed
30 with external screw threads, and a clamping
nut working on said screw threads and
adapted to bear against said flanges where-
by the collet holder may be fastened at dif-
ferent lateral adjustments of the cross head.

In testimony whereof I affix my signature ⁴⁵
in presence of two witnesses.

ERNEST B. JONES.
